Primary Examiner — Darlington Ly(74) *Attorney, Agent, or Firm* — Scott B. Markow(57) **CLAIM**

The ornamental design for a drain auger, as shown and described.

DESCRIPTION

FIG. 1 is a front and left side perspective view of a drain auger showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings illustrate portions of the drain auger that form no part of the claimed design.

1 Claim, 7 Drawing Sheets# US D830,806 S
